[57] CLAIM

The ornamental design for a combined holder for decanter and cups, substantially as shown and described.

DESCRIPTION

FIG. 1 is a front elevational view of a combined holder for decanter and cups, showing my new design;
FIG. 2 is a rear elevational view thereof;
FIG. 3 is a right side elevational view, the opposite side being substantially a mirror image thereof;
FIG. 4 is a top plan view thereof; and
FIG. 5 is a bottom plan view thereof.
